ABSTRACT: A metal refining plant in which molten metal is poured from a tilting induction furnace in a first vacuum chamber into molds contained within a second vacuum chamber. The two chambers are interconnected by way of a horizontally operable valve disposed between the two chambers. A tundish which is movable in both a horizontal and a vertical plane directs the molten metal through the valve into a mold positioned therebelow. Means are provided to preheat the tundish, and an auxiliary tundish is coupled to the first for use in an emergency. All operations are controlled and visible from the exterior.

**MULTIPLE TUNDISH SYSTEM FOR METAL REFINING
PLANT**

This invention relates to an apparatus and method for vacuum refining of molten metals. More particularly, it relates to a vacuum metallurgical refining plant in which there are vertically adjoining chambers interconnected through a valve. A tilting induction furnace is located in the first chamber which is connected to suitable air evacuation means. One mold at a time is positioned beneath the valve. A movable tundish which is adapted to be horizontally moved from a pre-heating station to a position over the valve can also be vertically lowered through the valve when the latter is in open position whereby the molten metal may be directed from the furnace into the molds, all under vacuum conditions. An auxiliary tundish is coupled to the first tundish and can be used during any emergency.

Heretofore, during the vacuum refining of metals using induction furnaces, it has been the practice to melt and pour the molten metal into molds all within a single vacuum chamber. As a consequence, one could not recharge the furnace nor remove the molds without breaking the vacuum. Accordingly, the operation became inefficient since the furnace could not be used to refine a fresh charge of metal while the molds were cooling, nor could molds be moved into the vacuum chamber while the melt was being degassed in the furnace. It was therefore necessary to perform the melting and refining operation in a first chamber, pour the molten refined metal into a ladle or other suitable carrying device, and then move the ladle into a second separate and independently operated chamber in which the molten metal was teemed into molds. While mold tunnel interlocks have been employed, these not only required large door valves through which the mold cars could pass but also they consumed considerable floor space.

It is therefore an object of this invention to provide an apparatus and method for vacuum refining and pouring metal into molds simultaneously without interfering with the recharging of the furnace while the molds are cooling or the removal of the molds while a fresh batch of metal is being refined.

Another object of this invention is to provide a metallurgical refining plant in which refined molten metal can be poured through a conduit directly into molds while the entire system is under vacuum.

Still another object of this invention is to provide a vacuum metallurgical refining plant which employs a tundish system to direct molten metal from an induction furnace through an intermediate valve into molds so as to minimize floor space and enable minimal size valve components to be utilized.

Yet another object of this invention is to provide a mobile tundish system in which an auxiliary tundish is attached to the main tundish and is adapted to be immediately employed in the event of an emergency, such as failure of the main tundish.

Still yet another object of this invention is to provide a means for preheating a tundish preparatory to its use for directing molten metal into molds.

A further object of this invention is to provide a dual-chambered vacuum melting and molding plant in which an intermediate valve is used to interconnect the refining and molding chambers in combination with a mobile tundish which can be conveniently positioned at a preheating station, at an inactive station, or at a pouring station.

Yet a further object of this invention is to provide a mobile tundish system for a valved dual-chambered vacuum refining and pouring plant in which the valve sealing elements are fully protected from molten metal drippings and heat radiations.

Still yet a further object of this invention is to provide a dual-chambered vacuum metallurgical refining plant in which the pour and teeming operations are all visible and operable from a single remote external station.

Yet still another object of this invention is to provide a dual chambered vacuum metal refining plant in which all refractory elements are conveniently exposed for maintenance.

Other objects of this invention are to provide an improved device of the character described which is easily and economi-

cally produced, which is sturdy in construction and both highly efficient and effective in operation.

With the above and related objects in view, this invention consists of the details of construction and combination of parts as will be more fully understood from the following detailed description when read in conjunction with the accompanying drawings in which:

FIG. 1 is an elevational sectional view of a metallurgical refining plant embodying the instant invention.

FIG. 2 is a sectional view taken along lines 2-2 of FIG. 1.

FIG. 3 is a sectional view taken along lines 3-3 of FIG. 2.

FIG. 4 is a sectional view taken along lines 4-4 of FIG. 2.

FIG. 5 is a sectional view taken along lines 5-5 of FIG. 4.

FIG. 6 is a sectional view taken along lines 6-6 of FIG. 4.

FIG. 7 is a sectional view taken along lines 7-7 of FIG. 6.

FIG. 8 is a sectional view taken along lines 8-8 of FIG. 7.

Referring now in greater detail to the drawings in which similar reference characters refer to similar parts, we show a vacuum refining apparatus comprising a melt chamber A having a metal refining furnace B enclosed therein, a mold chamber C or tunnel for holding molds D, a valve E interposed between the two chambers, and a movable tundish assembly, generally designated as F, which is adapted to direct metal poured from the furnace B into the molds D through the valve E thereabove.

Referring especially to FIG. 1, the melt vacuum chamber A is a reinforced steel housing and includes a lower section 12, a portion of which rests upon a structural bed 14. A cover 16 is detachably secured over the lower section 12 by a suitable flanged coupling 18 and can be rolled back to expose the contents thereof. The chamber A is of sufficient cubic dimensions to support and enclose the furnace B and is connected by a conduit 20 to an air evacuation means, such as a multistage, steamjet, high vacuum system (not shown). A suitable valved hopper 22 is mounted in the cover 16 so that the furnace B may charged under vacuum, if it is so desired. The furnace B may be any suitable high-temperature melting device for heating, melting, stirring, and refining metal, such as steel, under high temperature conditions. Preferably, it is a coreless induction furnace because of compatibility with an evacuated environment and by virtue of its ability to produce stirring as well as heating by eddy current developed thereby. The furnace B includes a generally cylindrical crucible 24, of 30-ton capacity for example, which has a pouring lip or spout 26. Suitable refractory lines the entire interior of the furnace.

The furnace B is supported by means of trunnions 28 laterally extending therefrom and pivotally supported in pillow blocks 30. Hydraulically actuated drive means (not shown) enables the furnace to be tilted forwardly approximately 105° for pouring molten metal into the tundish F. Means are also provided to back tilt the furnace approximately 30° from a vertical for cleaning and/or maintenance purposes.

The mold tunnel C is also a reinforced structural steel chamber which is separated from the melt chamber A by a vertical partition wall 32 and by a horizontal deck 34. A conduit 21 couples the mold tunnel C also to the air evacuation means through suitable valving (not shown) whereby vacuum may be applied to either the mold tunnel or the chamber A independently. The valve E is incorporated in the deck 34 so that a mold assembly D may be oriented directly under the valve aperture. A platform 36 is disposed outside the melt chamber A at approximately the level of the deck 34 whereby operating personnel at a single location can conveniently observe the pour from the furnace B into the tundish F through sight port 38 and the teeming from the tundish into the molds D via sight port 40.

The tundish assembly F is best illustrated in FIGS. 2 and 4. It includes a pair of side-by-side refractory lined channel members 42 and 44, the tundish 42 being used for normal operations and tundish 44 being an auxiliary standby or emergency unit. Each includes a generally cylindrical splash shield 46 at one end into which the molten metal is poured from the

lip 26 of the furnace B. A spout 48 at the other end conveniently funnels the molten metal flow into a stream. Weir 50 interposed at the downstream side of the tundish allows the molten metal heat to be skimmed of surface contaminants.

The operating tundish 42 and the auxiliary tundish 44 are both supported within a pie-shaped holder or rack 52. Concave rollers 53 and 54 journaled in bearings 56 at the bottom of the rack 52 engaged with and ride upon a liquid cooled arcuate pipe rail 58 which is supported on the deck 34.

The other end of the rack 52 includes an arm 60 which projects through opposed slots 62 and 64 in cylinder member 66. The arm 60 rests on a button 68 supported on the upper end of a piston 70 which is vertically reciprocable in the lower closed end of cylinder 66. A thrust bearing 72 rotatably supports the lower end of cylinder 66, the upper portion of which includes a shaft 74 journaled in bearing 76. Rotatable motion of the tundish F assembly about an axis defined by bearings 72 and 76, is produced by rotation of pinion 80 which is in engagement with bevel gear 82. Shaft 84 on bevel gear 82 is journaled in a sealed bearing 86 mounted in the circumferential wall 12 of chamber A. A motor drive unit 88-89 is mounted at the opposite end of shaft 84 outside of the chamber A and supported below skulling platform 90 for rotating the tundish F either in a clockwise or counterclockwise direction as desired. Shield 92 acts to protect the bevel and pinion gears from any splashing metal and/or radiant heat. The operator standing on the pouring platform 36 can observe pouring of the metal from the furnace A into the tundish F by way of sight port 38 or from the tundish into the molds by way of sight port 40.

The isolation valve E is essentially a large horizontally actuated water-cooled gate valve which is interposed within an opening in the deck 34 between the two chambers A and C, as best generally illustrated in FIGS. 1, 2 and 4. The details of construction of the valve E are best seen in FIGS. 6, 7, and 8. The valve E includes a housing portion 100 which includes opposed flanges 102 and 104 for coupling to conduit fittings. In this case flange 102 is bolted to a complementary ring 94 mounted within the deck opening. Flange 104 may have a cover plate 96 pivotally connected thereto which may be swung out of the way when the tundish spout 48 is inserted. A heat shield 98 is coupled to the ring 94 and tapers upwardly to an orifice somewhat larger than that of the tundish spout. The valve E is operated by a double-acting hydraulic cylinder 106 whose piston is connected to valve plate 108 through rod 110, guiding block 112 and levers 114. Draw springs 116 connecting the valve plates 108 prevent the latter from sliding on the inside of the housing wall 100 during horizontal in-and-out movement. When opening, the valve plate is first lifted from its seat before it is moved aside. A heat shield 118 overlies the surface of the valve plate to guard it from radiation. The piston rod 110 is sealed against vacuum by an oil bearing 120. Suitable reinforcing ribs 121 insure the maintenance of vacuum.

As is apparent from the foregoing description, the tundish F may be pivoted upwardly about its track 58 as a fulcrum by activating piston 70. For this position the tundish spout 48 is clear of the valve E as shown in dotted lines in FIG. 4. The tundish F may then be swung in a horizontal plane until it is situated under a canopy 122 defining a preheating station. A series of nichrome heat elements 124 serve to elevate the tundish to a temperature wherein its refractory will not be appreciably shocked and so that the molten metal being poured will not suffer too great a cooling effect during pouring.

The furnace chamber A is pumped down with the valve E closed. Molds D are run into the mold chamber C which is pumped down to the same vacuum as that in the chamber before the melt is poured. The valve E is opened and the tundish F rotated until in approximate registration with the furnace. The tundish spout 48 is next lowered through the valve E. From a position outside the chambers A and C, the operator on platform 36 tilts the furnace B forwardly while observing the pour through sight port 38. Teeming from the tundish into the mold D is visible through sight port 40. When all of the molds have been poured, the tundish F is elevated to clear the

spout 48. It is also to be noted that the tundish F may be raised by elevation of piston 70 so as to stop the flow of molten metal through the nozzle after filling each mold. The valve E may now be closed whereupon the furnace B can be recharged under vacuum or brought up to atmospheric conditions by rolling back the cover 16. Skulling of the furnace can be accomplished at this stage while the molds are cooling under vacuum. Conversely, while the melt in the furnace is being refined under vacuum the molds can be taken out of the mold tunnel C without interfering with operations in the melt chamber.

It is to be observed that by locating the valve E in a horizontal position vertically separating the two chambers A and C, the teeming through the spout 48 is vertical. At the same time, all of the refracting in both the tundish F and the furnace B is fully expressed for convenient cleaning when just the cover 16 is rolled back. In the event of failure of tundish 42, tundish 44 is available for immediate service.

Although this invention has been described in considerable detail such description is intended as being illustrative rather than limiting since the invention may be variously embodied, and the scope of the invention is to be determined as claimed.

We claim:

1. Metallurgical refining apparatus comprising a first chamber including furnace means for melting and refining metal therein, a second chamber including a horizontal portion extending at least partially within said first chamber, valve means interposed within said horizontal portion for isolating said first and second chambers from each other, means for opening and closing said valve means, means for evacuating said first and second chambers, conduit means including an inlet end for receiving molten metal from said furnace means, an intermediate channel portion for directing the molten metal along a substantially horizontal path, and a discharge end for vertically teeming the molten metal into a mold located therebelow, carriage means supporting said conduit means in said first chamber, first drive means for horizontally orienting said carriage means at a pouring position in which the inlet of said conduit means is in registration with metal being poured from said furnace and said discharge end is in registration with said valve means, second drive means for vertically displacing the discharge end of said conduit means from an elevated position over said valve means to a lowered position extending through said valve means when open, and means for moving molds into and out of said second chamber and aligning one mold at a time under the discharge end of said conduit means, whereby said first and second chambers can be independently and interdependently operated under vacuum conditions.

2. The apparatus of claim 1 including a heating station means in said first chamber horizontally displaced from said pouring position for preheating said conduit means before molten metal is poured therethrough.

3. The apparatus of claim 1 wherein said conduit means comprises a first tundish for performing the pouring operations and a second tundish coupled thereto for standby emergency operations in the event of failure at said first tundish.

4. The apparatus of claim 1 wherein said carriage means is pivotally supported about vertical and horizontal axes.

5. The apparatus of claim 4 wherein said carriage means includes an arcuate rail disposed in a horizontal plane, and means constituting rollers engaging said rail.

6. The apparatus of claim 5 wherein said roller means depend from one end of said carriage means, and means constituting a rotatable cylinder embracing the other end of said carriage means.

7. The apparatus of claim 6 including a piston in said rotatable cylinder engaging said other end of said carriage means.

8. The apparatus of claim 1 wherein said valve means constitutes a gate valve.

9. The apparatus of claim 1 in which all of said means are operable from a position external to said chambers.

10. The apparatus of claim 9 including means to view the pouring and teeming operation from a single station external to said chambers.
